UNITED STATES PATENT OFFICE.

AUBREY M. LEE, OF DALLAS, TEXAS, ASSIGNOR TO SIMPLEX ICE AND MANUFACTURING COMPANY, OF DALLAS, TEXAS, A CORPORATION OF TEXAS.

ICE-SCORING MACHINE.

Application filed May 23, 1927. Serial No. 193,452.

This invention relates to new and useful improvements in ice-scoring machines.

The invention relates to that type of machines set forth in my Letters Patent No. 5 1,521,449, issued December 30, 1924, and involves certain improvements thereover and departures therefrom.

An important object of the invention is to provide a feed drive separate from the 10 saw drive, so as to be independently controlled; and also to make said feed drive reversible so that the cake of ice may be run through the machine from either side.

A particular object of the invention is to 15 provide saw adjusting means, whereby the relative spacing of the saws and the consequent spacing of the scores may be controlled and regulated in a simple, easy and expeditious manner.

20 Another object of the invention is to provide horizontal guides for the cakes of ice in its passage through the machine, together with a single chain conveyor having guides for maintaining its engagement with 25 the ice cake; whereby the use of double chain conveyors is eliminated and more accurate and positive feed is had.

A further object of the invention is to 30 provide a hinged guard permitting the passage of the cakes of ice, but preventing the operator from falling into the machine between the saws.

A construction designed to carry out the 35 invention will be hereinafter described, together with other features of the invention.

The invention will be more readily understood from a reading of the following specification and by reference to the accompanying drawings, in which an example of the 40 invention is shown and wherein:

Fig. 1 is a side elevation of an ice scoring machine constructed in accordance with my invention.

Fig. 2 is an end elevation of the same.

45 Fig. 3 is a longitudinal sectional view taken on the line 3-3 of Fig. 2.

Fig. 4 is a transverse sectional view taken on the line 4-4 of Fig. 1.

50 Fig. 5 is a horizontal cross-sectional view taken on the line 5-5 of Fig. 1.

Fig. 6 is a transverse sectional view taken on the line 6-6 of Fig. 1.

Fig. 7 is a detail of the saw adjustment arm,

55 Fig. 8 is a side elevation of another form

in which the invention may be carried out, and

Fig. 9 is an end elevation of the same.

In the drawings the numeral 10 designates a base plate having upright frame members 60 11 and 12 respectively secured thereto on each side. Each side frame member is triangular in shape with its apex cut off, said frames preferably being constructed of angular metal bars and each having a sill 13 extending longitudinally of the frame. The frame also includes upright members or supports each comprising vertical standards 14 angular in cross-section. The standards 14 support a cap member 15 at their tops. 70

A pair of vertical saw shafts 16 are suitably supported at their lower ends in journal boxes 17 secured to the inner sides of the sills. Each shaft 16 has connection, by means of a coupling 18, with the armature 75 shaft 19 of a vertically disposed electric motor 20 supported on stools 21 securely fastened on the cap member 15. The shafts 16 are disposed centrally of the frame members 11 and 12, as well as centrally between 80 each pair of standards 14 of each frame member.

On each saw shaft I have shown four saws which I have designated by the letters A, B, C and D and ranging from top to bottom, 85 although the number of saws may be varied. Each saw has a hub 22 and the hubs of the saws A and B are fastened on the shafts by set screws 23 and are stationary thereon, but their elevation may be changed if 90 desired. The hubs 22 of the saws C and D each have key-ways 24 (Fig. 7) for receiving a key or spline 25 carried by their respective saw shafts. This permits the lower saws C and D to be adjusted vertically on 95 the saw shafts.

The saws are rotated by the shafts 16 and are located on each side of the machine so as to cut opposite sides of a cake of ice inserted therebetween. It is customary to 100 freeze ice cakes in rectangular form, the cake having a greater dimension longitudinally than transversely. Thus, when a cake is inserted with its greatest dimension vertically, it is said to be in the vertical or upright position and when it is inserted in the machine with its greatest dimension longitudinally, it is said to be in the horizontal or longitudinal position. When the cake is in its vertical position, its opposite sides will be 110

scored by all the saws. When it is in its horizontal position the cake will be scored either by the bottom saw D or both the saws C and D, according to the adjustment.

In order to adjust the saws correctly, the saws D on each side must be linked together so as to be raised or lowered at the same time and the saws C on each side must be likewise connected. I provide a pair of transverse hangers each comprising bars 26 disposed in the standards 14 and having vertical slots 27 receiving shouldered bolts 28 carried by the standards.

Each pair of bars 26 is connected by a cross-head 29 having a block 30 in its center. The bars 26 are slideable through the cap 15 as is best shown in Fig. 3. Brackets 31 are fastened on the cap and have vertical adjusting screws 32 rotatably confined therein. The screws have screw-threaded engagement in the blocks 30 and each has a hand-wheel 33 on its upper end. By rotating the hand-wheel, the hanger will be adjusted vertically by reason of the vertical movement of the block 30 on the screw 32. Each of the bars 26 of one of the hangers carries a saw bracket 34 which is rigidly attached thereto and has its outer end forked to engage in a circumferential slot 35 of the hub 22 of the saw C. Each of the bars 26 of the hanger carries a bracket arm 34' having its outer end forked to engage in a circumferential groove 35' of the hub 22 of the saw D, the parts described being of substantially the same construction. It will be seen that the saws C are collectively adjustable independently of the saws D and by turning one of the hand-wheels 33 the saws C may be adjusted, while by turning the other hand-wheel 33 the saws D may be adjusted.

The base plate 10 is made smooth so that a cake of ice may be readily slid between the frame members 11 and 12. In my patent hereinbefore referred to, I employed two chain conveyors and operated them by the saw operating motors. In my improved form, I employ only one chain conveyor and operate the same with a separate motor, whereby it may be individually controlled separate from the driving means of the saw.

In order to successfully use a single chain conveyor, I provide guide rails 36 disposed along the inner sides of the sills 13 and carried by studs 37 whereby they are spaced from said sills as well as being spaced from each other at such a distance as to prevent undue lateral displacement of the cake of ice when passing longitudinally therebetween. The ends of each guide rail 36 are curved outwardly toward the sill so as not to interfere with the introduction of the cake of ice. I have shown the rails formed of shallow channel members which are very satisfactory because they only present narrow surfaces to the cake and thus offer less

resistance to the passage of the cake of ice. Similar, but shorter, guide rails 38 are mounted on studs 39 carried by the standards 14 just below the tops of the frame members 11 and 12. The rails 38 have their ends bent outwardly as is shown.

The conveyor consists of an endless chain 40 travelling in angular guide members 41 and 42 secured respectively to the inner and outer sides of the frame member 11. At one end of the frame member 11 is mounted a bracket 43 carrying an upright stub shaft 44 on which a sprocket wheel 45 is journaled. The chain 40 passes around this sprocket wheel and also around a driving sprocket wheel 46 at the opposite end of the frame member. The sprocket wheel 46 is mounted on the upper end of a vertical drive shaft 47 protruding from a worm drive 48 which is mounted on a bracket 49. A horizontal guard plate 50 is fastened over the sprocket 46 and a similar guard plate 51 is fastened to the frame over the sprocket 45.

An electric motor 52 is mounted on the sill 13 of the frame member 11 and has its armature shaft 53 connected with the worm gear 48 whereby motion is imparted to the shaft 47 and the chain 40 propelled by means of the sprocket 46. By reason of the guide members 41 and 42 the chain 40 can not sag nor can it be displaced outwardly away from the cake of ice passing between the guide rails. The inner leg of the chain is disposed outwardly of the underlying guide rail 36 so as not to interfere with the passage of the cake of ice. This chain carries a single propelling finger 54 which extends at right angles to the chain and projects inwardly beyond the guide rail so as to engage one end of a cake of ice and slide it along the base plate 10 between the guide rails. One of the important features is the connection of a double throw switch 55 with the motor 52 whereby said chain 40 may be driven in either direction so as to carry the cake of ice through the machine from either side.

In using the machine the cake of ice is first introduced in its vertical position from the left hand end of the machine (Figs. 1 and 3). It is pushed onto the base plate 10 and between the guide rails 36 and 38 far enough for the finger 54 to swing in behind and engage the trailing vertical side of the cake. The saws A, B, C and D having been previously adjusted, the broad vertical sides of the cake of ice are scored as said cake is slid therebetween by the conveyor chain 40 and its finger 54.

To prevent the operator from falling into the machine from the right hand end, (Figs. 1 and 3) a U-shaped guard yoke 56 is hinged on a pintle 57 mounted at one end of the cap 15. The yoke has filler straps 58 swinging between the rails 38. A handle 59 is

rigidly attached to the cap above the yoke. The ice cake swings the guard outwardly and slides thereunder.

After the cake of ice has been scored in its vertical position, it is tilted to its horizontal position and slid onto the base plate 10 from the right hand end (Figs. 1 and 3) of the machine. The saws A and B will be above the cake and the wheels 33 are rotated to adjust the hanger bars 26 to vertically adjust the saws C and D. The switch 55 is adjusted to reverse the motor 52 so that the chain 40 travels through the machine from right to left (Figs. 1 and 3).

15 The guard yoke is held in position by stops 60 on the extreme right hand ends of the frame members 11 and 12 and the cake in its horizontal position will pass under the guard. It will be seen that in handling 20 the cake of ice, the workman could not fall toward the saws without striking the guard yoke. The cake of ice having been slid into the machine in its horizontal position will be engaged by the finger 54 and pushed between the saws C and D or merely the saw D, according to the adjustment. Shield plates 25 61 conforming to the general shape of the frame members 11 and 12 are hinged at their upper ends to the tops of said members.

30 Each shield plate has a pair of hooks 62 at its lower portion engaging the top flange of the adjacent sill, whereby said plates are inclined outwardly on the outside of the frame, thus shielding the workmen from the saws 35 and the conveyor chain.

In Figs. 8 and 9 I have shown another form of scoring machine involving certain features of the invention. In this form side frame members 11' and 12' are mounted on a base plate 10' and include sills 13'. Standards 14' secured to the sills and frame members support a cap 15'. Saw shafts 16' mounted in bearing boxes 17' are connected to motor shafts 19' by couplings 18'. Motors 20' are mounted on the stools 21' on the cap, all of the parts thus described are substantially like those of the other form of machine.

I have shown three saws A', B', and C' on each shaft, but this number is subject to change. The hubs 22' of the saws A' and B' are fastened on the saw shafts by set screws 23'. Each shaft 16' has a spline 25' and the hub 22 of the saw C' is mounted to slide thereon. A pair of hanger bars 26 are mounted in the standards 14' and have slots 27', receiving shouldered bolts 28', by which said bars are guided.

The bars are connected by a cross head 29' having an adjusting block 30' receiving a screw 32' rotatably confined in a bracket 31' and provided with a hand wheel 33'. A forked bracket 34' engages in a circular groove 35' on the hub of each saw C' and is secured to one of the bars 26. It will be

seen that the parts so far described are substantially the same as those set forth in connection with the first form except as to one pair of hangers and a pair of saws.

In this latter form the guide rails and the conveyor are omitted. For sliding a cake of ice in its vertical position through the machine from right to left (Fig. 8), I mount a T-shaped pusher bar or hand conveyor 70 in hanger guides 71 adjustably suspended from the cap 15', whereby said bar may be raised or lowered. On the ends of the bar I mount handles 72. A beveled dog 73 is notched and pivoted to the depending T of the pusher bar so as to swing. The dog is free to swing to the left (Fig. 8) but is prevented from swinging to the right by a stop 74. When the bar 70 is pushed to the left (Fig. 8) and there is a cake of ice in the machine, the dog 73 will engage the cake and the stop 74 will prevent swinging of the dog. Thus upon continued pushing of the bar, the cake will be pushed from the machine.

Various changes in the size and shape of the different parts, as well as modifications and alterations, may be made within the scope of the appended claims.

What I claim, is:

1. In an ice scoring machine, a frame, vertical saw shafts mounted on said frame, circular saws carried by said shafts, one saw on each shaft being adjustable vertically thereon, and a hanger carried by the frame and connected with said adjustable saws for adjusting the same.

2. In an ice scoring machine, a frame, vertical saw shafts mounted on said frame, circular saws carried by said shafts, one saw on each shaft being adjustable vertically thereon, a hanger carried by the frame and connected with said adjustable saws for adjusting the same, and means for sliding a cake of ice through the machine between the saws.

3. In an ice scoring machine, a frame, upright standards carried by the frame, a cap mounted on the standards, vertical saw shafts rotatable in the frame between the standards, circular saws carried by said shafts on each side of the frame, one saw on each shaft being adjustable vertically thereon, hanger bars mounted to slide vertically on the standards, connecting members attached to the hanger bars and with which said adjustable saws are engaged, a cross member for connecting the hanger bars, and means mounted on the cap and connected with said connecting means for vertically adjusting the hanger bars.

4. In an ice scoring machine, a frame, upright standards carried by the frame, a cap mounted on the standards, vertical saw shafts rotatable in the frame between the standards, circular saws carried by said

shafts on each side of the frame, one saw on each shaft being adjustable vertically thereon, hanger bars mounted to slide vertically on the standards, connecting members attached to the hanger bars and with which said rotatable saws are engaged, a cross member for connecting the hanger bars, means mounted on the cap and connected with said connecting members for vertically adjusting the hanger bars, and means for sliding a cake of ice through the machine between the saws.

5. In an ice scoring machine, a frame, upright standards carried by the frame, a cap mounted on the standards, vertical saw shafts rotatable in the frame between the standards, circular saws carried by said shafts on each side of the frame, one saw on each shaft being adjustable vertically thereon, hanger bars mounted to slide vertically on the standards, connecting members attached to the hanger bars and with which said rotatable saws are engaged, a cross member for connecting the hanger bars, means mounted on the cap and connected with said connecting members for vertically adjusting the hanger bars, and means for sliding a cake of ice through the machine between the saws, said sliding means being reversible for sliding a cake of ice through the machine in either direction.

6. In an ice scoring machine, a longitudinal base plate, upright side frame members mounted longitudinally on said plate, spaced upright standards secured to each frame member, whereby a receiving passage is provided between the frame members and standards for a cake of ice, a cap mounted on the upper ends of the standards, vertical rotatable saw shafts mounted between the standards on each side of the machine, horizontal circular saws mounted on said shafts and projecting into the passage between the frame members, means mounted on the cap for rotating the saw shafts, the lowermost saw on each shaft being vertically adjustable thereon and rotatable therewith, a hanger bar mounted to slide on one of the standards on each side of the machine, an adjusting arm extending from the hanger bar to the said lower saw, and means on the cap connected with the hanger bars for vertically adjusting the same.

7. In an ice scoring machine, a longitudinal base plate, upright side frame members mounted longitudinally on said plate, spaced upright standards secured to each frame member, whereby a receiving passage is provided between the frame members and standards for a cake of ice, a cap mounted on the upper ends of the standards, vertical rotatable saw shafts mounted between the standards on each side of the machine, horizontal circular saws mounted on said shafts and projecting into the passage between the

frame members, means mounted on the cap for rotating the saw shafts, the lowermost saw on each shaft being vertically adjustable thereon and rotatable therewith, a hanger bar mounted to slide on one of the standards on each side of the machine, an adjusting arm extending from the hanger bar to the said lower saw, means on the cap connected with the hanger bars for vertically adjusting the same, and a conveyor member movable longitudinally of the machine for engaging and sliding a cake of ice along the base plate and between the saws.

8. In an ice scoring machine, an upright frame, vertical saw shafts rotatably mounted in the frame, a plurality of circular saws mounted on each shaft and some of said saws being vertically adjustable, hangers mounted in the frame, connections between the hangers and the adjustable saws, a pair of adjusting screws mounted on the frame each having connection with a hanger, means for rotating said screws to vertically move the hangers and adjust the saws, a chain conveyor carried by the frame, guide rails carried by the frame for receiving a cake of ice therebetween, and means for driving said conveyor.

9. In an ice scoring machine, the combination of a saw mounted at each side of the machine in a position to cut a horizontal kerf, and means for simultaneously adjusting the saws vertically, substantially as set forth.

10. In an ice scoring machine, the combination of a pair of spaced saws mounted in a manner to cut kerfs on opposite sides of a cake of ice in the same relative position and substantially parallel to one side of the machine, and means for simultaneously adjusting the saws at right angles to the kerf which they cut, substantially as set forth.

11. In an ice scoring machine, an upright saw shaft mounted at each side of the machine, one or more pairs of oppositely disposed saws mounted on said shafts to make kerfs on opposite sides of a cake of ice in the same relative position, and means for simultaneously adjusting one or more pairs of said oppositely disposed saws longitudinally of their shafts without changing their relative positions, substantially as set forth.

12. In an ice scoring machine, a pair of spaced parallel saw shafts, pairs of saws mounted on said shafts in a manner to make kerfs in the same relative position on the opposite sides of a cake of ice, and means for simultaneously adjusting one or more of said pairs of saws longitudinally of their shafts without changing their relative positions, substantially as set forth.

13. In an ice scoring machine, a pair of spaced parallel saw shafts, pairs of saws mounted on said shafts in a manner to make kerfs in the same relative position on the

opposite sides of a cake of ice, means for simultaneously adjusting one or more of said pairs of saws longitudinally of their shafts without changing their relative positions, and a movable guard at one end of the machine, substantially as set forth.

14. In an ice scoring machine, a pair of spaced parallel saw shafts, pairs of saws mounted on said shafts in a manner to make 10 kerfs in the same relative position on the opposite sides of a cake of ice, means for simultaneously adjusting one or more of said pairs of saws longitudinally of their shafts without changing their relative positions, and a shield plate mounted at each

side of the machine outwardly of the saws, substantially as set forth.

15. In an ice scoring machine the combination of an upper set of scoring saws mounted in position to cut horizontal kerfs 20 on opposite sides of a cake of ice, a lower set of scoring saws mounted also in position to cut horizontal kerfs on opposite sides of the cake of ice, and means for simultaneously adjusting the lower set of scoring saws 25 toward and from the upper set of saws, substantially as set forth.

In testimony whereof I affix my signature.

AUBREY M. LEE.
